UNITED STATES PATENT OFFICE

116,750

DESIGN FOR A LADY'S COAT

Sidney Passin, New York, N. Y.

Application June 15, 1939, Serial No. 85,499

Term of patent 3½ years

To all whom it may concern:

Be it known that I, Sidney Passin, a citizen of the United States and a resident of the city of New York, in the county of Kings and State of New York, have invented a new, original, and ornamental Design for a Lady's Coat, of which the following is a specification, reference being had to the accompanying drawing, forming a part thereof.

Fig. 1 is a front view of a coat showing my design.

Fig. 2 is a rear view of the coat shown in Fig. 1.

The pleated panel and the collar are of a different fur than that employed on the balance of the garment.

I claim:

The ornamental design for a lady's coat, substantially as shown and described.

SIDNEY PASSIN.
